(57) **CLAIM**

The ornamental design for a low profile electronic device as shown and described.

DESCRIPTION

FIG. 1 is a front perspective view of a low profile electronic device such as a thermostat showing the new design;

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a top view of a second embodiment of a low profile electronic device showing the new design. All other views of the second embodiment are identical; and,

FIG. 9 is a top view of a third embodiment of a low profile electronic device showing the new design. All other views of the third embodiment are identical.

The ornamental design claimed is shown in solid lines in the drawings. Broken lines, if present in the drawings, are for illustrative purposes only and form no part of the claimed design. The stippling in FIGS. 6, 8, and 9 is used to indicate a contrast in appearance between the transparent lens and the front surface of the electronic device, with no specific color, material, texture, or other feature being claimed. The stippling does not indicate a contrast in appearance between the front surface of the electronic device and portions of the electronic device other than the transparent lens.
